CYLINDER

Earl Giles Jordan, Moweaqua, Ill.

Application October 26, 1944, Serial No. 560,413

3 Claims. (Cl. 123—57)

This invention relates to a cylinder, and more particularly to such a cylinder adapted to be utilized in conjunction with internal combustion engines.

The primary object of this invention is the provision of an improved cylinder adapted to provide relatively great compression with a comparatively short stroke.

An additional object of this invention is the provision of such a cylinder provided with an internal bore of two sizes adapted to accommodate a two-step piston, and provided with means whereby air from a larger bore is forced into the smaller bore by the action of the piston and compressed therein.

Still another object is the provision of such a cylinder having passages through the walls thereof extending from the larger bore into the smaller bore, and terminating below the top of the bore or the maximum compression stroke of the piston.

Still another object resides in the provision of such a cylinder which will be reliable and efficient in operation, sturdy and durable in construction, relatively simple and inexpensive to manufacture, and which will provide a relatively high compression in comparison to that provided by cylinders hitherto known.

Other objects reside in the combinations of elements, arrangement of parts, features of construction, which will be more fully pointed out hereinafter and shown in the accompanying drawings wherein there are disclosed several preferred embodiments of this inventive concept.

In the drawings—

Figure 1 is a side view partially in elevation and partially in section showing one form of cylinder embodying this inventive concept in association with a piston.

Figure 2 is a sectional view taken substantially along the line 2—2 of Figure 1.

Figure 3 is a top plan view of the device shown in Figure 1, the cylinder head being removed.

Figure 4 is a sectional view taken substantially along the line 4—4 of Figure 1.

Figure 5 is a side sectional view of a modified form of this invention.

Figure 6 is a sectional view taken substantially along the line 6—6 of Figure 5 as viewed in the direction indicated by the arrows.

Figure 7 is a side sectional view of a still further modified form of this invention, and

Figure 8 is a top plan view of the device shown in Figure 7, certain parts thereof being indicated by dotted lines.

Like reference numerals refer to like parts throughout the several views of the drawings.

Having reference now to the drawings, more particularly to Figures 1 to 4, inclusive, there is generally indicated at 10 a cylinder, comprised of a cylinder wall 11, within which is cut a bore 12 of relatively large diameter, terminating adjacent the upper portion of the cylinder in a shoulder 13. A reduced bore 15 is cut into the upper portion of the cylinder, whereby to provide in the same cylinder two bores of different diameters.

Extending from the face of shoulder 13 to the interior of bore 15, at a point below the upper extremity thereof, are a plurality of passages 16.

As best shown in dotted lines in Figure 1, the upper portion of cylinder 10 is adapted to be provided with a cylinder head generally indicated at 20, comprised of a head portion 21 having suitable bores 22 extending therethrough into a recess 23 formed directly above the top of bore 15, and having valves 24 provided with valve stems 25 seated in such bores, to permit the intake of air to the cylinder.

A piston, generally indicated at 26, is positioned within the cylinder, and is comprised of a cylindrical portion 27 of a diameter adapted to conform to the bore 12 and a second cylindrical portion 28 extending upwardly therefrom and adapted to engage in the bore 15. Suitable piston rings 29 are positioned peripherally about the cylindrical portion 27, and a conventional piston rod 30 is mounted in the customary manner as on a wrist pin 31.

From the foregoing, the operation of the device should now be readily understandable.

On the compression stroke of the cylinder, effected in the customary manner, air within the bore 12 is compressed and forced upwardly through the passages 16, into the upper portion of bore 15. Simultaneously the air in bore 15 is compressed by the piston portion 28. As the piston continues its upstroke and passes the openings of passages 16 within bore 15, a further compression of the air, both that originally contained in bore 15 and that forced from bore 12 through passageways 16, is effected, until such time as the mixture of air and fuel within the cylinder is exploded in the conventional manner by a spark plug (not shown). It will thus be seen that a greater compression of air may be effected due to the concentration of the air in the two bores previously mentioned, with a relatively short stroke of the piston 26.

Having particular reference now to Figures 5 and 6, there is disclosed a modified form of this

invention adapted particularly for application to presently constructed motors, and so arranged that the improved cylinder and piston may be applied within the existing cylinder. In this modification, there is disclosed a cylinder generally indicated at 40 provided with a cylinder wall 41 having a relatively large bore 42 therein, a shoulder 43 adjacent the upper portion of the cylinder comprising a portion of a block 44, within which is cut a reduced bore 45, and passageways 46 leading from bore 42 to bore 45.

A piston generally indicated at 47, comprised of a relatively large cylindrical portion 48 adapted to fit within bore 42 and a smaller portion 49 adapted to fit within bore 45, is positioned within the cylinder, and connected to a piston rod 50 as by means of a wrist pin 51. Piston rings 52 are provided to seal the piston within the cylinder, and, as in the foregoing modification, the extremities of passageways 46 terminate below the top surface of the cylinder 40.

A peripheral flange 53 is positioned about the top of cylinder 40, and provided with a plurality of threaded holes 54 therein. A cylinder head 55 is adapted to be seated on cylinder 40 and is provided with inlet passages 56 having one-way valves 57 positioned therein, adapted to be biased to closed position as by springs 58. A conventional spark plug 59 is positioned in the cylinder head 55, adapted to explode the mixture in the cylinder. Cylinder head 55 is so dimensioned as to extend outwardly over the flange 53 and is provided with bores 60 adapted to be aligned with the bores 54. Bolts 61 are adapted to be passed through bores 60 and bores 54, and engage in suitable threaded apertures in the engine block in alignment therewith, to hold the cylinder and cylinder head assembly in position within the engine block.

Thus it will be seen, by means of the device shown in this modification, a complete cylinder assembly, including a head, may be readily attached to any conventional make of internal combustion engine.

The operation of the modification just above described is substantially identical with that of the operation of the modification previously discussed.

Having reference now to Figures 7 and 8, there is disclosed a still further modified form of this inventive concept, wherein a cylinder, generally indicated at 70, is comprised of a side wall 71 having a relatively large bore 72 therein, a shoulder 73, comprising a portion of the thickened upper wall 74 of the cylinder, and surrounding a relatively small bore 75. Positioned within the cylinder 70 is a piston 76 comprised of a relatively large cylindrical portion 77 adapted to engage the bore 72 and a smaller portion 78 adapted to engage the bore 75, provided with piston rings 79 and mounted on a piston rod 80 as by means of a wrist pin 81.

Passageways 82 lead from the face of shoulder 73 through angularly inclined channels 83 to outlets 84 in the upper portion of bore 75.

From the upper portions or extremities of bores 82, additional bores 85 extend upwardly to the top of the cylinder 70, and are positioned in alignment with bores 86 in a cylinder head 87. The upper extremities of bores 86 terminate in inlets 88. Positioned within the aligned bores 85 and 86 are the valve stems 89 of one-way inlet valves 90, biased as by springs 91 to its closed

position, and adapted to be opened by the vacuum in the cylinder on the down stroke of piston 76. The central portion of the under side of the head 87 is provided with a recess 92, from which a relatively large bore 93 leads to a large inlet 94. A valve 95 is adapted to close bore 93, and is provided with a valve stem 96 biased toward closed position as by a spring 97 engaging the head 98 of the valve stem, and extending through an aligned aperture 99 in outlet 94.

A spark plug 100 is provided and extends through a suitable bore 101 into the interior of recess 92. Suitable bolts 102 are adapted to secure the head and the cylinder in related assembly.

The operation of this modification is substantially similar to that described in next to the foregoing modification, with the exception that upon the intake stroke of the piston, valves 90 are opened to admit air directly into the large bore 72 through the passageways 82, simultaneously with the opening of valve 95.

From the foregoing, it will now be seen that there are herein provided devices accomplishing all the objects of this invention and others including many advantages of great practical utility and commercial importance.

As many embodiments may be made of this inventive concept, and as many modifications may be made in the embodiments hereinbefore shown and described, it is to be understood that all matter herein is to be interpreted merely as illustrative and not in a limiting sense.

I claim:

1. In a device of the character described in combination, a cylinder head, a cylinder body having a relatively large bore therein, a shoulder in said cylinder comprising a face and a thickened portion of said body, means forming a reduced bore in said thickened portion, means forming passageways extending from said shoulder through said portion to the interior of said reduced bore, means forming inlets through said cylinder head and said thickened portion, to said passageways, and a piston in said cylinder.

2. In a device of the character described in combination, a cylinder head, a cylinder body having a relatively large bore therein, a shoulder in said cylinder comprising a face and a thickened portion of said body, means forming a reduced bore in said thickened portion, means forming passageways extending from said shoulder through said portion to the interior of said reduced bore, means forming inlets through said cylinder head and said portion to said passageways, valves in said passageways, and a piston in said cylinder.

3. In a device of the character described in combination, a cylinder head, a cylinder body having a relatively large bore therein, a shoulder in said cylinder comprising a face and a thickened portion of said body, means forming a reduced bore in said thickened portion, means forming passageways extending from said shoulder through said portion to the interior of said reduced bore, means forming inlets through said cylinder head and said portion to said passageways, valves in said passageways, and a piston in said cylinder, said piston including a large portion adapted to fit within said first bore and a reduced portion adapted to fit within said reduced bore in said cylinder.

EARL GILES JORDAN.
